UNITED STATES PATENT OFFICE

2,087,505

COMFORTER

Julius Davis, New York, N. Y.

Application March 13, 1937, Serial No. 130,625

1 Claim. (Cl. 5—334)

This invention relates to devices such as comforters.

One object of the invention is to provide a device of the character described having an improved filling which is not materially more expensive than an ordinary wool filling and which possesses substantially higher resilience than a wool filling and affords the heat retaining qualities of an all-down filling.

10 Devices such as all-down comforters are expensive by reason of the cost of the down, and the considerable labor involved in manufacture. Such comforters are made by first stitching a design through the case and leaving openings in the 15 lines of stitching for the insertion of a tube into different resulting sections of the case to blow down into the sections. Thus shifting of the down is prevented especially since the openings are finally closed. Also the possibility of down 20 working through the minute openings formed by the stitches is avoided.

It has been known to provide a filling bat consisting of a mixture of wool and down, to thus reduce the cost of the comforter without wholly 25 eliminating certain advantages of the down. Such a filling could be stitched to the case walls, so that the mode of manufacture was simplified. But as the down was caught in and restrained by the wool, there was relatively little resilience in 30 the mass, and the heat retaining quality was not substantially greater than that of an all wool filling.

Accordingly I devised an article such as a comforter which shall combine the natural warmth, 35 and resilience of wool as a body forming element, with a relatively small quantity of down arranged in concentrated form and in such manner as to be immediately and directly available in the use of the comforter, and without creeping of the 40 down through the stitching-formed openings.

A further object of the invention is the provision of a device such as a comforter having relatively few and simple parts and which is durable, reliable and efficient in use to a high degree.

45 Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a plan view of a device such as a comforter embodying the invention.

Fig. 2 is a sectional view taken on the line 2—2 of Fig. 1.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device such as a comforter embodying the invention. The same may be constructed according to my patent application, Serial No. 116,682, filed December 19th, 1936, for Methods of making comforters, of which the present application is a division.

The comforter 10 may include a closed down-proof case 11 consisting of a suitable limp material such as a textile fabric. The case includes side walls 12 suitably marginally interconnected at 13. Within the case is a filling comprising a layer or pad 14 of a woolly material, and which may desirably be in the nature of a bat of suitably commingled or relatively loosely intertwined woolly fibers. For example, carded wool in intermixed condition can be used to provide a bat of desired consistency, and with the requisite qualities of weight, resilience and heat retaining qualities. In any event, the bat is preferably as loose and fluffy in texture as possible. The bat may afford wooly side faces and its edges 15 may be spaced inward somewhat of the seams 13.

Between the pad or bat 14 and at least one side 40 wall 15 of the case is provided a layer 16 of a downy material. To render the comforter reversible, such layer 16 may be provided between each face of the pad 14 and the adjacent case wall 12. Each layer 16 consists of free or loose downy material, such as down of the duck family; and the layers may each be substantially thinner than the pad 14. It is contemplated that the consistency of the layers 16 may be substantially the same as that which normally obtains in any 50 all-down comforter.

Preferably, the downy layers 16 may be in direct contact with the woolly surfaces of the pad 14, whereby the latter serves somewhat to restrain possible shifting of the downy material.

5 A single means is utilized to permanently prevent any substantial movement of the layers 14 and 16 in the case 11. Thus stitching 17 extends through the case walls 12 and the pad 14 and the downy layers 16 along a plurality of lines or points spaced substantially throughout the comforter, to thus anchor the parts of the latter to each other.

10 At the lines of stitching 17, the downy layers 16 are substantially subdivided into sections, with the case walls 12 closely approaching the pad 14 into virtual contact therewith. In this manner the comforter case is subdivided into compartments, but the important significance of this construction is that the creeping of downy fibers through the fine openings in the case walls which are formed in course of stitching is prevented. In other words, the pad 14 serves to block entrance to said openings, and any downy material 15 therat tends to lie flat and in compressed condition. The method by which this construction is accomplished may be best understood as follows: In general, an elongated sewing machine presser foot acts with considerable pressure on 20 the comforter so as to work a case wall 12 to move aside the downy material that is in advance of the needle. A suitable projection in general similar to the pressure may be provided for a like purpose on the sewing machine table, so that both 25 sides of the comforter may be similarly treated. Thus a satisfactory comforter can be made according to the invention without permitting shifting of the downy material at the lines of stitching 17.

30 35 It will be noted that since the pad edges 15 are spaced from the case edges at 13, the intervening

space may become filled with downy material as at 18. This will produce a soft edge for the comforter. Moreover, since the pad edge portions are not secured to the case 11, they may float somewhat to facilitate soft and easy curling or 5 folding of the edge portions of the comforter.

It will be understood that the pad 14 may consist of wool intermixed with cotton, silk or the like. In fact, the pad 14 may consist of any material which is soft and yielding. Preferably 10 such material is fibrous and somewhat loose in texture for suitably accommodating the down, with a minimum of crushing of the latter in actual use, particularly as a relatively small quantity of down is used. The downy material may 15 vary in character, it being sufficient that it shall be highly fluffy and hairy.

It will now be seen that I have provided a 20 device which fulfills the objects of the invention and is well adapted for practical use. 20

I claim:

A comforter, including a downproof case of a limp material; a bat of loosely intertwined wooly fibers therein; a relatively thin layer of loose down between a wall of the case and a side of the 25 bat and in contact with the latter; and lines of quilting stitching through said case, said bat and said layer of down; the down layer being so thin at said lines of stitching, and the said case wall being so closely in contact with the fibers of the 30 bat at said lines of stitching that the down at the lines of stitching is all entangled with the bat fibers sufficiently to prevent escape of down through the stitch holes.

JULIUS DAVIS. 35
